AERIAL TOY

William Clifford Knox, Jr., Seattle, Wash., assignor to
Knox Instruments, Inc., Seattle, Wash., a corporation
of Washington

Filed Oct. 2, 1961, Ser. No. 66,951

Term of patent 14 years

(Cl. D34—15)

FIG. 1

FIG. 2

FIGURE 1 is a top plan view showing my new design
of an aerial toy.

FIG. 2 is an elevational view thereof.

The characteristic feature of my design resides in the combination on the aerial toy disclosed of the longitudinally dished wheel configuration having a narrow rim and wide spokes meeting in a domed hub and an inverted mushroom shaped handle element, all as shown.

I claim:
The ornamental design for an aerial toy, as shown and described.
